UNITED STATES PATENT OFFICE.

OSCAR EISENHUTH, OF DETROIT, MICHIGAN, ASSIGNOR OF ONE-HALF TO
JACOB S. SNYDER, OF SAME PLACE.

BUNG AND BUSHING.

SPECIFICATION forming part of Letters Patent No. 368,139, dated August 9, 1887.

Application filed June 6, 1887. Serial No. 240,352. (No model.)

To all whom it may concern:

Be it known that I, OSCAR EISENHUTH, a citizen of the United States, residing at Detroit, in the county of Wayne and State of Michigan, have invented certain new and useful Improvements in Combined Bungs and Bushings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention is designed for closing the filling or bung-holes of barrels and kegs, being especially designed for beer-kegs; and it consists in the construction and combination of parts forming a metallic bung and bushing, as hereinafter set forth, and pointed out particularly in the claim.

20 In the accompanying drawings, forming a part of this specification, Figure 1 is an isometrical view of the device embodying my invention, showing the handle for locking the bung removed. Fig. 2 is a section in elevation, taken on the dotted line $\alpha\alpha$ of Fig. 1, showing also a section of a keg. Fig. 3 is a perspective of the bushing-ring (looking into the upper end) having the bung removed.

25 In the drawings, B designates the metal ring or bushing, having on its outer periphery the screw-threaded surface S. The upper or outer end has the flange F, with angular surface a on its periphery to receive a wrench to enable the screwing of the bushing-ring into the hole of a keg. The periphery of the flange is octagonal in form. An annular chamber, R, is formed in the upper half of the bushing 30 extending down to the annular flange f, and J is a smaller chamber passing through the bushing.

I form in the flange F, on opposite sides, the vertical channels Z Z', communicating with the inclined channels Z' Z', having near the lower end in the upper wall a notch or recess, e. (See Fig. 3.)

45 C is a metal cap having an oval top, W. Crossing said top is a channel, d, having inclined or undercut sides t t. (See Figs. 1 and 2.) The upper portion of the cap is made to

register with and pass freely into the chamber R of the bushing-ring, (see Fig. 2,) and has on its outer periphery the annular flange or shoulder O. The cap is hollow, as shown at E, 55 having on its lower end the cylinder Y, which freely passes through the chamber J of the bushing B.

I locate on the outer periphery of the bung or cap C, and at right angles to the channel d, 60 the lugs or pins V V, which have a slight projection. (See Fig. 2.) The projection of each pin is equal to the depth of the channels Z Z, and the pins are adapted to pass freely into said channels, engaging therewith. 65

D is a handle having the shoulders i i and stem K, with beveled edges n n. The stem is adapted to be slid into the channel d of the cap, for the purpose of turning said cap or bung, and to lift it out of the bushing when 70 unlocked, as hereinafter specified.

The parts are to be operated as follows: To insert the bushing into the hole of the keg H, a wrench is applied to the flange F. Turning the wrench causes the bushing to enter the 75 keg. When sufficiently secured, a leather or flexible washer, P, is placed on the annular flange f, the bung C is placed into the bushing, its lugs or pins V V entering the vertical channels Z Z of the bushing. Then the arm 80 K of the handle is passed into the channel d of the bung or cap C, and by swinging said handle around in the direction of the arrow in Fig. 1 the cap is caused to revolve, forcing the lugs V along the inclined channels Z', thus 85 drawing the annular shoulder O onto the washer P and closing the parts. The cap is to be revolved until the pins V meet the notches e, when the pressure of the washer P will force said pins slightly upward into the notches, 90 thus preventing the cap or bung from working loose. All of this is shown in Figs. 2 and 3.

When the cap is locked, the handle D is removed. To unlock said parts the handle is inserted into the cap C, and by giving a slight 95 jerk on the handle (in an opposite direction to that indicated by the arrow in Fig. 1) the pins V V will move out of the notches along the channels Z' Z until they enter the vertical channels Z Z, when lifting on the handle the 100 cap will be removed from the bushing.

Having thus set forth my invention, what I

claim as new, and desire to secure by Letters Patent, is—

In a device for the purposes specified, the combination of the bushing having the threaded portion S and flange F, the vertical channels Z, the inclined channels communicating therewith, the annular flange f, and the bung or cap having the studs V, the channel d, with undercut edges, and handle D, for revolving

10 said cap, and the packing located between the shoulder O of the cap and annular flange of the bushing, as and for the purposes specified.

In testimony whereof I affix my signature in presence of two witnesses.

OSCAR EISENHUTH.
